PULP SCREEN

Wilfred F. Mathewson, Boston, Mass., assignor to
 Mathewson Machine Works, Inc., Quincy, Mass.,
 a corporation of Massachusetts

Application December 10, 1948, Serial No. 64,540

3 Claims. (Cl. 92—35)

1

In my U. S. Patent No. 2,450,838, October 5, 1948, there is described and illustrated a paper pulp screen comprising a casing having an inlet for the unscreened pulp and a screened-pulp outlet, and pulp screening means within the casing comprising two concentric cylindrical screen members providing between them an annular clearance space of sufficient size for the fine acceptable portion of the unscreened pulp to pass therethrough, but of insufficient size for the coarse unacceptable portion of such pulp to pass therethrough. In the device of said patent the outer screen member is formed on its inner face with a plurality of vertically extending grooves, certain of which grooves constitute inlet grooves and have communication with the inlet to the casing and the remainder of which grooves constitute discharge grooves and have communication with the screened-pulp outlet. The screening of the pulp is accomplished by flowing from the inlet grooves to the clearance space and through said clearance space to the discharge grooves and thence to the screened-pulp outlet. As stated above the clearance space is such as to allow the acceptable portion of the pulp to pass therethrough but will prevent the coarse or unacceptable portion of the pulp to pass.

In the device of the said patent also the outer screen member having the inlet and discharge grooves is stationary while the inner screen member is rotatably mounted to turn about the axis of the concentric cylinders.

The device of the present application operates on the same principle as that of the above-mentioned Patent No. 2,450,838, but it differs from the device of said patent in that the inlet and discharge grooves are formed in the inner rotatable screen member and said grooves are endless grooves which extend circumferentially of said inner member and completely around the latter.

The device of the present application also differs from that of said patent in other particulars as will be more fully hereinafter set forth.

I have illustrated the present invention as it might be embodied in a laboratory model pulp screen rather than in a full-size commercial pulp screen, but the construction and operation of the screen elements is the same in both types of pulp screens.

In the drawings:

Fig. 1 is a side view of a laboratory model pulp screen embodying the invention.

Fig. 2 is a front view thereof.

Fig. 3 is a bottom plan view.

Fig. 4 is a vertical sectional view through the

2

casing and screen members taken on the line 4—4, Fig. 6.

Fig. 5 is a similar section with the inner screen member turned 90° from the position shown in Fig. 4.

Fig. 6 is a section on the line 6—6, Fig. 4.

Fig. 7 is a section on the line 7—7, Fig. 4.

Fig. 8 is a side view of the outer screen member, and

10 Fig. 9 is a fragmentary side elevation of the inner screen member.

In the drawings 1 represents the casing of the pulp screen which is provided at its lower end with an inlet chamber 2 to which the unscreened pulp is delivered and is provided at its upper end with a discharge chamber 3 into which the screened pulp is delivered, said discharge chamber having communication with a delivery pipe 4 for the screened pulp. The two concentric substantially cylindrical screen members are indicated at 5 and 6, 5 being the outer screen member and 6 the inner screen member which is located within the outer screen member. The two screen members are substantially cylindrical and they are constructed to form between them an annular clearance space 7 which has a width sufficient for the fine acceptable portion of the paper pulp to pass therethrough but which has an insufficient dimension to allow the coarse unacceptable portion of such pulp to pass.

15 In the present construction the outer screen member 5 is stationarily mounted in the casing 1, and the inner screen member 6 is a rotary member, it being mounted on and rotated by a shaft 8.

20 The inner screen member 6 is provided with one or more interior chambers 9 which open through the bottom thereof and thus communicate directly with the inlet chamber 2 of the casing but have no communication with the discharge chamber 3 except through the clearance space and the grooves to be presently described.

25 Said inner member 6 is also provided with one or more additional interior chambers 10 which communicate directly with the discharge chamber 3 of the casing through ports or passages 13 formed in the top of said inner screen member 6, said chambers 10 having no communication with the inlet chamber 2 except through the grooves to be presently described and said clearance space.

30 The inner screen member 6 is formed with a plurality of parallel, endless grooves which extend circumferentially thereof and completely thereabout, all of which grooves open into the clearance space 7.

Certain of said grooves, those indicated at 11, also communicate with the interior chambers 9 as shown in Figs. 4 and 7, while the other grooves, those indicated at 12, communicate with the other interior chambers 10 as best seen in Figs. 6 and 5. During the pulp screening operation, the unscreened pulp which is delivered to the inlet chamber 2 will flow into and fill the chambers 9. Said pulp will flow through the inlet grooves 11 into the clearance space 7 and will pass through said clearance space into the discharge grooves 12 from which the pulp is delivered to the chambers 10 that communicate through openings or passages 13 with the discharge chamber 3 of the casing.

Inasmuch as the clearance space 7 is so formed as to allow only the fine acceptable portion of the pulp to pass therethrough, the pulp which is delivered to the discharge grooves 12 and thence to the chambers 10 will be only properly screened pulp.

The coarse unacceptable portion of the pulp which cannot pass through the clearance space 7 will tend to accumulate at the mouth of the inlet grooves 11, and in order to prevent such accumulation from clogging the screen, I have provided means for periodically flushing each inlet groove.

For this purpose the outer stationary screen member 5 is provided with one or more openings 14 situated to register with each inlet groove 11, said openings leading into a tailings-receiving chamber 15 with which the casing 1 is provided and which encircles the outer screen member 5. The openings 14 thus provide a communication between the clearance space 7 and the tailings-receiving chamber 15. The portions of the outer screen member 5 which are opposite or register with the discharge grooves 12 are solid, the openings 14 being situated only opposite and in register with the inlet grooves 11.

If at any time during the screening operation some of the coarse unacceptable portion of the pulp becomes clogged at the mouth of any inlet groove 11, then when such obstruction comes opposite an opening 14 during the rotation of the inner screen member 6, such obstruction or unacceptable portion of the pulp will flow through the opening 14 into the chamber 15 from whence it is delivered through the delivery pipe 16.

Since the inner screen member 6 is continuously rotating, each inlet groove 11 will be continuously flushed so as to prevent any of the coarse and unacceptable portion of the pulp from accumulating in the clearance space and interfering with the screening operation.

In the construction shown the outer screen member 5 is provided with three flushing openings 14 for each inlet groove, but the number of such openings may be varied without departing in any way from the invention.

The rotary inner screen member 6 may be supported within the outer screen member 5 in any suitable or approved way. As herein shown there is provided a step bearing 17 carried by the casing 1 and on which the screen member 6 rests as best seen in Figs. 4 and 5. This step bearing is shown as screw threaded through the bottom 18 of the casing 1 and hence can be adjusted vertically as required. It is held in its adjusted position by the set nut 19.

In the illustrated embodiment of the invention, while the screen members 5 and 6 are substantially cylindrical, yet they are shown as slightly tapered, the screen member 6 having a

slightly smaller diameter at its upper end than at its lower end. An advantage of this construction when used with the adjustable step bearing 17 is that by adjusting said bearing vertically, the dimension of the clearance space 7 can be changed to suit different pulp screening requirements.

As stated above, the present invention is shown as it might be embodied in a laboratory model pulp screen, which, of course, is built on a much smaller scale than a full size commercial machine. In the device herein shown the casing 1 is secured by a bracket 20 to a backing board 21 that may be secured to the wall of a building. This backing board 21 also supports a motor 22, the shaft of which is connected with the shaft 8 of the inner screen member 6 through a reducing gearing 31. The power output shaft 23 of the reducing gearing is connected with a shaft 8 through a universal joint 24.

25 indicates a supply tank containing unscreened pulp which may also be mounted on the backing board 21 above the motor. The unscreened pulp is delivered from the tank 25 to the inlet chamber 2 through a suitable pipe connection 26, 27 that leads into the chamber 2. The pipe 26 may conveniently be provided with a shut off valve 28.

With this construction the unscreened pulp is delivered to the chamber 2 at the bottom of the casing and then flows upwardly through the interior chambers 9 and through the inlet grooves 11 into the clearance space. The screened pulp which is delivered through the discharge grooves 12 passes through the clearance space into the interior chambers 10 and then flows upwardly through the passages 13 to the discharge chamber 3 and through the discharge pipe 4.

The casing 1 may be provided with any suitable bearing 29 for the shaft 8 and will preferably also be provided with any usual liquid seal 30.

I claim:

1. A pulp screen comprising a casing having an inlet for unscreened paper pulp and a screened-pulp outlet, two concentric substantially cylindrical screen members located within the casing and providing between them an annular clearance space of sufficient size for the fine acceptable portion of the unscreened pulp to pass therethrough, but of insufficient size for the coarse unacceptable portion of such pulp to pass therethrough, the inner screen member having in its peripheral face a plurality of parallel, endless grooves extending circumferentially thereof and completely thereabout, certain of said grooves constituting inlet grooves and the remainder constituting discharge grooves, said inner screen member having provision for connecting the inlet grooves to the casing inlet and also for connecting the discharge grooves to the screened-pulp outlet, the outer screen member having a plurality of openings communicating with the clearance space, one opening being situated opposite each inlet groove, and means to rotate the inner screen member, said openings in the outer screen member providing for flushing away the unacceptable portion of the pulp.

2. A pulp screen comprising a casing having an inlet for unscreened pulp and a screened-pulp outlet, two concentric screen members located within the casing and providing between them an annular clearance space of sufficient size for the fine acceptable portion of the unscreened

pulp to pass therethrough but of insufficient size for the coarse unacceptable portion of such pulp to pass therethrough, the inner screen member having an interior chamber which communicates with the casing inlet and another chamber which communicates with the screened-pulp outlet, said inner screen member also having a plurality of endless grooves extending circumferentially thereof and completely thereabout, all of which grooves open into the clearance space and certain of which grooves constitute inlet grooves and open into the first mentioned interior chamber and the remainder of which grooves constitute discharge grooves and communicate with the other interior chamber, and means to rotate the inner screen member.

3. A pulp screen comprising a casing having an inlet chamber at its lower end to receive unscreened pulp and also having a discharge chamber at its upper end to receive screened pulp, two concentric screen members located within the casing between the inlet chamber and discharge chamber, said screen members providing between them an annular clearance space of sufficient size for the fine acceptable portion of the unscreened pulp to pass therethrough but of insufficient size for the coarse unacceptable portion of such pulp to pass therethrough, the inner screen member having an interior chamber which is open at its lower end

15

20

25

30

to the inlet chamber of the casing and also having another interior chamber which is open at its upper end to the discharge chamber of the casing, said inner screen member further having a plurality of endless grooves extending circumferentially thereof and completely thereabout, all of which grooves are open to the clearance space and certain of which grooves constitute inlet grooves and communicate with the first mentioned interior chamber and the remainder of which grooves constitute discharge grooves and communicate with the other interior chamber, and means to rotate said inner screen member.

WILFRED F. MATHEWSON.
